UNITED STATES PATENT OFFICE.

PAUL HAHN, OF ELBERFELD, GERMANY, ASSIGNOR TO THE FIRM OF I. W. SPEAR & SÖHNE, OF NUEREMBERG, GERMANY.

TOY.

No. 839,138.

Specification of Letters Patent.

Patented Dec. 25, 1906.

Application filed February 16, 1906. Serial No. 301,475.

To all whom it may concern:

Be it known that I, PAUL HAHN, a citizen of the Empire of Germany, residing at Elberfeld, in the Empire of Germany, have invented a new and useful Toy, of which the following is a specification.

My invention relates to a figure—for example, representing an animal—which is adapted to be moved upward on an inclined 10 plank by repeatedly drawing a string attached to its hind legs. Several such figures and inclined planks may form a racing game.

I will now proceed to describe my invention with reference to the accompanying 15 drawings, in which—

Figure 1 is an elevation of an inclined plank and a figure in its normal position, partly in section. Fig. 2 is a similar view and represents the figure after its hind legs, under the 20 action of the drawn string, have moved forward and engaged in the next following indent of the plank. Fig. 3 is a cross-section through the same, and Fig. 4 is a perspective view of a racing game.

Similar letters of reference refer to similar parts in the several views.

The toy consists in a figure, which may represent an animal, in this case a pig *b*, and is provided with fast fore legs *g* and movable 30 hind legs *a*. It is adapted to climb or run on an inclined plank *h*, provided with indents *i i*. The body of the figure is provided with a deep cavity *k*, in which a two-armed lever *l* is mounted to rock on a pin *c* or pins *c c*. The 35 upper arm of the lever *l* is connected with the front inside of the cavity *k* by means of a helical spring *f*, which normally holds the lever *l* in the position shown at Fig. 1. The lower arm of the lever *l* is to represent the hind legs 40 *a a* of the figure, and a string *d* is attached to this lower arm at *m*. This string *d* passes from the hind legs *a a* forward to the front inside of the cavity *k*, then through an eye *e* rearward between the two hind legs *a a*.

The toy is operated as follows: The string *d* is seized with one's fingers and placed rearward, and the pig *b* is put on the plank *h* at its lower end, so that its hind legs *a a* engage in the first indent *i* close to the edge of the 45 plank *h*. Of course the fore legs *g* of the figure will engage in the respective indent *i* and

will be thereby checked on the string *d* being pulled in the direction of the arrow to move the hind legs *a a* forward. The latter will engage in the next following indent *i*, while 55 the helical spring *f* will be strained, as is shown at Fig. 2. On the string *d* being released the spring *f* will draw the upper arm of the lever *l* forward, so that it will cause the fore legs *g* to move forward and to engage in 60 the next following indent *i*, since the hind legs *a a* are checked by the respective indent *i*. On again pulling the string *d* the figure *b* will be caused to move forward through a distance like the pitch of the indents *i i*. In 65 this manner the figure *b* can be moved upward on the plank *h* by repeatedly drawing the string *d*.

Several toys and inclined planks may be combined to form a convenient racing game, 70 as is illustrated, for example, at Fig. 4.

The toy described may be varied in many respects without departing from the spirit of my invention. It may represent any other animal or a human being on the inclined 75 plank. The spring *f* may be arranged to act on the lever *l* by pressure.

What I claim as my invention, and desire to secure by Letters Patent, is—

1. A toy of the class described, comprising 80 an inclined plank with indents, and a figure of suitable design climbing on said plank, it having fast fore legs, which engage in any indent, and movable hind legs, which engage in any other indent, a spring having one end 85 connected to the figure and its other end to the hind legs for moving the hind legs rearward and a string attached to the hind legs and passing forward to an eye at the figure and thence rearward and being adapted to 90 move the fore legs forward into the next indent while straining said spring.

2. The combination with an inclined plank 95 provided with indents, of a figure provided with a cavity and with fast fore legs which engage in any indent of said inclined plank, a two-armed lever mounted in the cavity of said figure to turn and its lower arm representing the hind legs which can engage in any indent of said inclined plank, a spring in the 100 cavity of said figure and acting upon the upper arm of said two-armed lever, an eye on

the front inside of the cavity of said figure, a
string passing from the lower arm of said
two-armed lever to said eye and thence rear-
ward and adapted to move the fore legs of
5 said figure into the next indent of said in-
clined plank while straining said spring.

In testimony whereof I have signed my

name to this specification in the presence of
two subscribing witnesses.

PAUL HAHN. [L. S.]
